DELIVERY MECHANISM FOR PRINTING MACHINES

Joseph E. Meyer, Jackson Heights, N. Y., assignor,
by mesne assignments, to R. Hoe & Co., Inc.,
New York, N. Y., a corporation of New York

Application November 15, 1933, Serial No. 698,083

19 Claims.

(Cl. 93—93)

This invention relates to certain improvements in delivery mechanisms for printing machines and more particularly to a mechanism for dividing or arranging the product of such a machine 5 in evenly divided sets to facilitate the counting of same.

Among the objects of this invention, one is to provide a delivery mechanism which has a means for gripping each product as it is released from the folder of a printing machine and which is 10 adapted to maintain said grip until the product is about to be ejected.

Another object is to provide a means whereby certain gripping members are periodically opened 15 somewhat in advance of their regular order of opening and to provide a means to eject the product from the grippers at these periods.

In general, the structure involved in this invention comprises a rotatable cylinder having a plurality of evenly spaced gripper fingers mounted 20 therein, said fingers having a gripper portion projecting beyond the surface of the cylinder and adapted to be moved when in engagement with the product of a printing machine or other similar machine, to grip and advance same to a normally positioned stop, whereupon the grip is released and the product is ejected. A predetermined number of products are ejected in this manner and deposited upon a conveyor in evenly 25 spaced relation. After the desired number of products have been deposited in this manner, an auxiliary stop and gripper release mechanism is then actuated which is adapted to release and eject one product somewhat in advance of the 30 normal release and ejecting position, to cause said latter product to project beyond the edge surface of the evenly spaced products when deposited upon the conveyor. In this manner, the products will be divided into sections, with an equal number 35 of products in each section and with one projecting product in each section to mark same.

With the above and other objects not specifically referred to in view, the invention consists in certain novel parts, arrangements and combinations which will be fully described in connection with the accompanying drawings and the novel features pointed out in the claims hereunto annexed.

In the drawings which show a preferred embodiment of the invention:

Figure 1 is a vertical sectional view taken on the line 1—2 of Figure 3, showing a cross section through the cylinder with the gripper actuating and ejecting mechanism shown in normal operating position, also showing guide means through

which the product is released from the press folder and a conveyor to receive same;

Figure 2 is a view similar to Figure 1 but showing the parts in a position at the time one product is ejected in advance of the normal order of 5 ejection; and

Figure 3 is an elevational view taken in the direction of the arrow 3 of Figure 1, with parts broken away.

Referring now to the details of construction, a 10 cylinder 11 is rotatably mounted in bearings 12 which are supported by side frames 13, only one of which is shown, and is driven in any suitable manner.

Above said cylinder 11, a suitable guide mechanism 14 is provided through which the product of a printing press folder is adapted to pass, and which guides said product to align same with a gripping portion of a gripping mechanism to be hereinafter described.

Below said cylinder 11, a suitable conveyor 15 is provided, upon which the product is deposited after it is ejected from the gripper mechanism.

Said gripper mechanism comprises a plurality of fingers 16 having supporting lugs 17 secured 25 thereto and fixed to shafts 18, which shafts 18 are suitably mounted in end walls 19 of said cylinder. The ends 21 of the gripper fingers 16 extend outward through openings 22 in the circumferential wall 11a of the cylinder and are 30 bent inward to provide a gripper portion for same.

Arms 23, fixed to the ends of shafts 18, as shown in Figure 3, have cam rollers 24 mounted on the ends thereof, which rollers ride over the cam surface 25 of a stationary cam 26, bolted to 35 the frame 13.

Fixed stop arms 27, are arranged to project into the path of the moving product when in engagement with the gripper fingers and may be mounted in any convenient manner. As shown 40 in the drawings, each fixed stop comprises a bar mounted in a bracket 28, with said bracket secured to a rod 29 mounted in the frames 13. The upper end of said bar is curved and extends into a recess 31 provided in the circumferential wall 11a.

As thus far described the mechanism will function in the following manner.

The product P, Figure 1, passes from the press folder through the guide mechanism 14 and approaches the cylinder 11 just as the gripper portion 21 of the gripper fingers 16 are closing in on the surface of the cylinder 11, whereby said product is clamped between the finger and the cylinder surface and moved therewith until the stops 50 55

21 are reached. Just prior to the engagement of the product with said stops, the gripping tension of the finger 16 is released, which thus permits the product to be ejected or stripped from said 5 fingers and cylinder when it strikes the stop arm 21. Each of the gripper fingers is manipulated in the same manner to pick up and release each product, and since the fingers are equally spaced around the cylinder, the products will be ejected 10 therefrom and deposited on the conveyor 15 in substantially equally spaced relation.

The means provided for counting the products comprises a mechanism which is adapted to eject one of every predetermined number of products, 15 somewhat in advance of the normal order of ejection, and thereby cause same to extend out from those products on the conveyor which were ejected in their normal order. For example, let it be considered that every twenty-fifth product is to 20 extend beyond the edge of the evenly spaced run of products deposited on the conveyor. This extended product would then function as a marker or guide to simplify the counting of the products.

The mechanism involved in the latter operation 25 consists of movable stop members 32, each having an arm 33 secured to a rock shaft 34 and a forwardly disposed extension 35, which is adapted to lie within a groove 31 of the cylinder wall 11a, out of the path of the gripped product, 30 when the products are being run off in normal order or evenly spaced relation.

A cam shoe 36 is pivotally mounted at 37 within a cavity 38, in the stationary cam 26, and has one cam surface 39.

35 A rocker lever 41 is secured to the rock shaft 34 and has a roller 42 mounted on one arm thereof. A turnbuckle 43 has one end connected to another arm of said rocker lever 41 at 44 and its other end connected to the cam shoe 36 at 45. A 40 rotatable cam 46 is mounted on a driven shaft 47, which shaft is carried in bearings in the frame 13, and is provided with a cam surface 48 upon which the roller 42 rides.

During the normal run of said products, the 45 parts of the mechanism are positioned as shown in Figure 1, with the movable stop 32 and the cam shoe 36 positioned in an inoperative location. When the raised portion 49 on the cam 46 engages the roller 42, the shaft 34 is rocked, which rocking 50 motion swings the extension 35 on the movable stop 32, downward into the path of the product, and also causes the cam shoe 36 to be moved downward to present its cam surface 39 to the approaching cam roller 24. A new cam surface and 55 a new stop at the edge 51 of the extension 32, is thus momentarily provided to release and eject the product somewhat in advance of the normal order of ejection. The cam roller 42 then moves off the raised cam portion 49 and the rocker lever 41 is rocked, which movement will cause the movable stop 32 and the cam shoe 36 to be moved to their inoperative position as shown in Figure 1.

It is to be understood that both the cam roller 60 42 and the cam rollers 24 will be maintained in engagement with their respective cam surfaces 48 and 25 by any suitable means such as springs (not shown).

It is therefore obvious from the foregoing 70 that the structure as described herein will function in a simple and efficient manner and that the positive gripping features of the fingers 16 and the auxiliary gripper release and ejecting mechanism as provided by the cam shoe 36, and the 75 movable stop 32, are important improvements in

connection with counting mechanisms of this character.

While the invention has been shown and described in its preferred form, it will be understood that certain changes and variations may be made in the specific structure provided for carrying out the invention without however departing from the spirit of the invention as defined in the appended claims.

What I claim is:

1. In a delivery mechanism for a printing machine, a cylinder having grippers for handling cut products, means for operating the grippers, a conveyor to receive the products, a stop located to strip the products from the cylinder and position same on the conveyor when released by the grippers, a second stop, and means for opening the grippers prematurely as certain of said products are stripped by the second stop. 15

2. In a delivery mechanism for a printing machine, a rotatable cylinder having grippers for handling cut products, a cam to control the movement of said grippers, a conveyor to receive the products, a stop to strip the products from the cylinder and position same on the conveyor when released by the grippers, a second stop, and means for opening the grippers prematurely as certain of said products are stripped by the second stop. 20

3. In a delivery mechanism for a printing machine, a rotatable cylinder having gripper fingers extending beyond the surface thereof to grip the products of a printing machine and deliver same to a stripper, a cam means to control the grip and release of said grippers, a conveyor to receive the product, a stop to strip certain products from the cylinder and position same upon the conveyor in evenly spaced relation when released by the grippers, a second stop, and means for opening the grippers prematurely as certain other of said products are stripped by the second stop. 30

4. In a delivery mechanism for a printing machine, a rotatable cylinder having gripper fingers extending beyond the surface thereof to grip the products of a printing machine and deliver same to a stripper, a cam means to control the grip and release of said grippers, a conveyor to receive the product, a fixed stop to strip certain products from the cylinder and position same upon the conveyor in evenly spaced relation when released by the grippers, a second stop movable into the 45 path of certain products, and means for opening the grippers before the engagement of said latter products with the second stop to thereby deposit said latter products in an offset relation to the first named products. 50

5. A delivery mechanism for a printing machine, including a guide for the product thereof and a conveyor for receiving said product, grippers movable into the path of said product and adapted to grip same, a normal stop positioned 60 in the path of said product, means for releasing the grip before the product engages said stop, whereby a certain number of products are positioned on the conveyor in equally spaced relation, a movable stop, and a means cooperating with 65 the movable stop for prematurely releasing the grip upon a product, whereby certain products are positioned in an offset relation to the equally spaced products.

6. A delivery mechanism for a printing machine, including a guide for releasing the product thereof and a conveyor for receiving said product, cam actuated gripper fingers movable into the path of said product and adapted to grip and move same, a normal stop positioned in the path 75

of said product, a means for releasing said grip before the product engages said stop, thereby permitting successive products to be delivered to the conveyor in equally spaced relation, and a 5 cam actuated movable stop member and finger grip release means adapted to be actuated at predetermined intervals to release one of every predetermined number of products in advance of the normal order of release and permit same to be 10 offset from the equally spaced products.

7. A delivery mechanism for a printing machine, including a guide for releasing the product thereof and a conveyor for receiving said product, a rotatable cylinder, fingers projecting from said 15 cylinder, cam actuating means therefor adapted to move said fingers into engagement with the product and release same at a fixed location, a fixed stop member to engage the product at said fixed location, whereby a predetermined number 20 of products are released and permitted to drop on said conveyor in equally spaced relation, a movable stop, and finger grip release means adapted to control the release of one of every predetermined number of products, whereby the 25 latter is offset from the equally spaced products to mark equal divisions of same.

8. A mechanism for counting the product of a printing machine folder, including in combination, a plurality of grip fingers arranged in evenly 30 spaced relation, means for successively bringing said fingers into gripping engagement with each product as it is released from the folder, a normal stop adapted to be engaged by a predetermined number of said products, whereby they are 35 ejected and become piled in evenly spaced relation, an auxiliary stop, and finger grip release with means for actuating same periodically to eject certain predetermined products out of the normal order, whereby the said latter named 40 products are offset from the evenly spaced products.

9. A mechanism for counting the product of a printing machine folder, including in combination, a rotatable cylinder, gripper fingers mounted 45 therein having a gripper portion extending beyond the periphery thereof, cam actuated arms for rocking said fingers into and out of engagement with the product, fixed stop members adapted to be engaged by certain products when released by the gripper fingers to eject and deposit same upon the conveyor in equally spaced relation, a movable stop normally positioned out of the path of the moving product, a movable cam shoe cooperating with said movable stop, and means for 50 actuating said movable stop and cam shoe at predetermined periods to eject certain products ahead of their normal order of ejection and thereby position same in an offset relation to the 55 equally spaced products.

60 10. A mechanism for counting the product of a printing machine folder, including in combination, a rotatable cylinder, gripper fingers mounted within said cylinder and having a gripper portion extending beyond the periphery thereof, a stationary gripper cam, arms adjoining said gripper fingers adapted to be rocked by said gripper cam, whereupon the gripper fingers are successively brought into gripping engagement with the products as they are released from the folder, a stationary 65 stop member adapted to eject said products from the gripper fingers to deposit same in evenly spaced relation, a movable stop member, a movable cam shoe, and a cam actuated rocker arm adapted to bring said movable stop and cam shoe into operative relation with the gripper 70

finger arms periodically and thereby cause one of every predetermined number of products to be deposited in an unevenly spaced or offset relation to indicate an exact division between said offset products. 5

11. A mechanism for counting the product of a magazine press folder, including in combination, a conveyor, a rotatable cylinder, rods equally spaced within said cylinder and gripper fingers secured to said rods, said gripper fingers extending through openings in the wall of said cylinder, rocker arms secured to the ends of said rods, a stationary cam adapted to rock said arms and gripper fingers to cause same to be moved into engagement and disengagement with the surface 15 of said cylinder and thereby grip each product released from the folder, a normal stop means adapted to engage said product and a predetermined number of same in succession as they are released from their gripper fingers, a movable 20 stop arranged to be brought into engagement periodically with one of every predetermined number of products, a movable cam shoe adapted to open the gripper fingers and release the last named products prior to their engagement with 25 the movable stop, and means for actuating said movable stop and cam shoe, whereby the first named products are deposited in evenly spaced relation upon a conveyor and the latter products are deposited in an offset relation to the first 30 named products.

12. A mechanism for counting the product of a magazine press folder, including in combination, a conveyor, a rotatable cylinder, rods equally spaced within said cylinder and gripper fingers 35 secured to said rods, said gripper fingers extending through openings in the wall of said cylinder, rocker arms secured to the ends of said rods, a stationary cam adapted to rock said arms and gripper fingers to cause same to be moved into 40 engagement and disengagement with the surface of said cylinder and thereby grip each product released from the folder, a normal stop means adapted to engage said product and a predetermined number of same in succession as they are 45 released from their gripper fingers, a movable stop normally positioned within the wall of the cylinder, a movable cam shoe normally positioned within a cavity in the gripper cam, and means for actuating said movable stop and cam shoe to 50 open the gripper fingers and eject certain products somewhat in advance of the normal order of ejection, whereby certain products are ejected and deposited in evenly spaced relation upon a conveyor and certain products are ejected ahead 55 of the normal order to position same in an offset relation to the evenly spaced products.

13. In a delivery mechanism for a printing machine, a cylinder having grippers for handling cut products, means for operating the grippers 60 to release the products, a conveyor to receive the products, means to strip the products when released by the grippers and position same on the conveyor in a normal order, and means to open said grippers and strip certain of said products 65 in advance of their normal order, whereby the said certain products will be displaced with reference to the other products on the conveyor.

14. In a delivery mechanism for a printing machine, the combination of means to receive the 70 products from the printing machine, means to retain the products on the receiving means, stop means to remove the products from said receiving means at regular intervals and periodically at other intervals in the machine operation, and 75

means to release the products from said retaining means before actuation of said removing means at each interval.

15. In delivery mechanism for a printing machine, a product retaining device to hold a product upon a product receiving means, a conveyor to which the products are delivered from said receiving means, timed mechanism operative to actuate said device to release the product held thereby periodically at different intervals and in either of two different positions, and product removing means operative to remove the product from said product receiving means in either position in which it is so released and cause it to be delivered to said conveyor in the position it is released.

16. In delivery mechanism for a printing machine, a product receiving means, a conveyor to which products are delivered from said receiving means, a product retaining means to hold a product upon said receiving means and being normally operative to release a product therefrom and deliver it to said conveyor, and timed mechanism periodically operative to actuate said product retaining means to release a product from the retaining means at a point other than the point at which it is normally released therefrom and deliver it to said conveyor.

17. In a delivery mechanism for a printing machine, means to retain products upon a machine part, means to actuate said retaining means at regular intervals to release products therefrom, means associated with said actuating means to remove the products as released thereby, a conveyor to which the products are delivered as they are released, means to actuate said retaining means to release products therefrom at other than regular intervals, means associated with said second mentioned actuating means to remove the products as they are released there-

by and deliver them to said conveyor, and timed means to render one of said retaining means actuating means, and its associated product removing means operatively ineffective, while the other, and its associated product removing means, is in operation.

18. In a delivery mechanism for a printing machine, means to retain products upon a machine part, means to actuate said retaining means at regular intervals to release products therefrom, means associated with said actuating means to remove the products as released thereby, means to actuate said retaining means to release products therefrom at other than regular intervals, means associated with said second mentioned actuating means to remove the products as they are released thereby, means to connect one of said retaining means, actuating means, and its associated product removing means together, for substantially simultaneous operation, and timed means to render one of said retaining means, actuating means and its associated product removing means operatively ineffective while the other and its associated product removing means is in operation.

19. In a delivery mechanism for a printing machine, the combination of means to receive the products from the printing machine, means to retain the products on the receiving means, a conveyor to which the products are delivered from the receiving means by said retaining means, and variable means to operate the retaining means to release products in sequence at regular intervals and deliver them to said conveyor, and timed means to vary said operating means to cause it to operate said retaining means to periodically release a product at other than the regular intervals and deliver it to said conveyor.

JOSEPH E. MEYER. 40
